FIG. 4

UNITED STATES PATENT AND TRADEMARK OFFICE
CERTIFICATE OF CORRECTION

PATENT NO. : Des. 516,593 S
APPLICATION NO. : 29/204088
DATED : March 7, 2006
INVENTOR(S) : Billy Earl Thomas

It is certified that error appears in the above-identified patent and that said Letters Patent is hereby corrected as shown below:

On The Title Page:

Acting sua sponte on a mistake discovered in the title pursuant to 35 U.S.C. 254, it is hereby certified that the correct title of this patent should be the title as shown below:

“BAKING SODA BOX HOLDER FOR USE WITH A REFRIGERATOR RACK”

The claim is corrected to read:

“ I claim

The ornamental design for a baking soda box holder for use with a refrigerator rack, as shown and described. ”

The description of FIG. 1 should read:

“FIG. 1 is a perspective view of a baking soda box holder for use with a refrigerator rack showing my new design; ”

Signed and Sealed this

Fourteenth Day of November, 2006

JON W. DUDAS
Director of the United States Patent and Trademark Office
